DISPLAY AND SHIPPING CARTON

Robert S. Ghiselin, Chicago, Ill., assignor to
 Lewis-Howe Company, St. Louis, Mo., a corporation of Delaware

Application March 13, 1937, Serial No. 130,622

3 Claims. (Cl. 206—44)

My invention relates to cartons for shipping small containers and for displaying them after shipment. The invention has for its principal objects a carton in which the small containers are so mounted as to be securely held during shipment and yet are attractively mounted for display purposes after shipment. The invention consists principally in a carton having slots in its body in which small containers may be mounted edgewise and a cover which may be folded over against the edges of said containers during shipment, and which may be straightened up after shipment to expose the containers and to display suitable advertising matter. The invention further consists in the display and shipping carton, in the blank and in the parts and combinations and arrangements of parts hereinafter described and claimed.

In the accompanying drawings,

Fig. 1 is a perspective view of an outside shipping case of common type,

Fig. 2 is a perspective view thereof with one end open and a portion of my display and shipping carton projecting therefrom,

Fig. 3 is a perspective view of said display and shipping carton,

Fig. 4 is a front elevation thereof, with the cover member straightened up to constitute a display,

Fig. 5 is a top plan view,

Fig. 6 is a sectional view on the line 6—6 of Fig. 5,

Fig. 7 is a sectional view on the line 7—7 of Fig. 5,

Fig. 8 is a sectional view on the line 8—8 of Fig. 5,

Fig. 9 is a plan view of the blank for making said carton; and

Fig. 10 is a plan view of a mounting sheet adapted for use in said carton to brace the containers mounted therein.

As shown in Fig. 1, my display and shipping carton A is adapted to be mounted, for shipping purposes, in a suitable shipping case B having an end flap 1. The display and shipping carton includes a top body panel 2 in which are a plurality of slots 3 in which small containers 4 of medicinal tablets or the like may be mounted edgewise. These slots 3 may be disposed as desired, preferred arrangement being a middle row of slots 3 arranged parallel with the front edge of the body, two rows of obliquely arranged slots on either side of said middle row. Thus, containers 4 mounted edgewise in said slots 3 have a considerable portion of their tops 5 exposed so

that one or more of said tops will be easily visible regardless of the angle from which one looks at the carton. In addition, the containers 4 as a group are arranged in an attractive pattern.

When the carton is on display, a panel or cover flap 6 is raised up to expose the containers 4 and forms a suitable background for the containers that will be covered with suitable descriptive and advertising matter. In shipment, said panel is folded over against the containers.

In Fig. 9 is illustrated the blank from which the carton is made. The upper panel is the display and cover flap 6 which is hingedly connected with the top body panel 2 along a score line 7. The cover and display flap 6 is itself scored along a line 8 to form a hinge flap 9 of a height substantially equal to the distance that the containers 4 project above the body panel 2. A bottom body panel 10 equal in size to the top panel 2 is connected therewith by a front wall 11, score lines 12 being provided to facilitate folding. At the rear of the bottom body panel 10, that is, at the lower margin thereof in Fig. 9, is a rear wall or flap 13 which is scored along a line 14. When the carton is assembled, said score line 14 registers with the score line 8 of the display flap 6 to permit folding of the assembled flaps.

Projecting from each side of the top body panel 2 are side panels 15 which are hingedly connected to closure flaps 16 along score lines 17. Projecting from the edges of the front wall 11 and the rear wall 13 are tongues 18 which cooperate with slots 19 provided in the closure flaps 16 to lock the carton in assembled position.

Preferably a sheet 20 with depressed ribs 21 to hold it above the bottom of the carton is placed inside the carton. Said sheet 20 has slots 22 that align with the slots 3 in the top body panel 2. Thus the lower portions of the containers 4 may be inserted in said slots 22 in said sheet and the sheet 20 acts as a brace for said containers.

The back panel flap 13 is preferably secured to the display flap 6 by means of a suitable adhesive 23. After the containers 4 have been mounted in the carton, the cover flap 6, carrying with it the back flap 13, may be folded over against the edges of the containers 4 into the position shown in Fig. 3. The carton may then be placed in a shipping case B, as shown in Figs. 1 and 2. After shipment, the display and shipping carton A may be removed from the shipping case B and the cover and display flap 6 folded up into display position as shown in Fig. 4. It then constitutes a

background and advertisement for the goods packed in the small containers.

Obviously, numerous changes may be made without departing from the invention and I do not 5 wish to be limited to the precise construction shown.

What I claim is:

1. A display and shipping carton for smaller containers, comprising a top body panel having 10 openings to receive containers, a bottom body panel, a front end wall connecting said top and bottom panels, a display and cover flap at the rear edge of said top panel, said flap being scored along a line parallel with the edge of the top panel 15 so that the major portion of said flap can be folded over parallel to said top, and a rear end wall, said rear end wall projecting above said top panel and being scored in register with said score in said display and cover flap.
- 20 2. A blank for a display and shipping carton for smaller containers, comprising a top body panel having openings, a bottom body panel, a front end wall between said top and bottom panels and hingedly secured thereto by score lines, a display and cover flap at the rear edge of said top panel hingedly secured thereto by a score line, said

flap being scored along a line parallel with the edge of the top panel to form a hinge flap, and a rear end wall, said rear end wall being scored to form a portion equal in width to the height of said front end wall plus the height of said hinge flap. 5

3. A blank for a display and shipping carton for smaller containers, comprising a top body panel having openings, a bottom body panel, a front end wall between said top and bottom panels 10 and hingedly secured thereto by score lines, a display and cover flap at the rear edge of said top panel hingedly secured thereto by a score line, said flap being scored along a line parallel with the edge of the top panel to form a hinge flap, a rear 15 end wall, said rear end wall being scored to form a portion equal in width to the height of said front end wall plus the height of said hinge flap, side flaps hingedly connected to said top body panel by score lines, closure flaps hingedly secured to said side flaps by score lines and locking tongues projecting from said front and rear end walls, said closure flaps being slotted to receive 20 said tongues.
